UNITED STATES PATENT OFFICE

FREDERICK W. VODOZ, OF WILMETTE, ILLINOIS, ASSIGNOR TO GOODMAN MANUFACTURING COMPANY, OF CHICAGO, ILLINOIS, A CORPORATION OF ILLINOIS

DRILLING MECHANISM

Application filed September 20, 1928. Serial No. 307,073.

This invention relates to improvements in drilling mechanisms particularly adaptable for use in coal mines and has for its principal object to provide a new and improved portable drilling mechanism so arranged that a motor more powerful and heavier than is usual in portable drilling mechanisms may be used to overcome the difficulties encountered in burning out said motors due to their lack of power to efficiently and continuously perform the drilling operations.

Other objects of my invention will appear from time to time as this specification proceeds.

The general practice in coal mining operations is to drill the coal with a hand operated post drill or small portable electric drill. Drilling by hand has proven to be very slow and expensive. While drilling with a portable electric drill is faster than hand drilling, in order to make said mechanism portable and easy to handle, said mechanism is often made too light to give satisfactory and economical results.

In carrying out my invention I provide an improved form of drilling mechanism so combined and carried with a portable truck as to afford sufficient strength to withstand all strains subjected to it due to drilling, said truck providing a means for supporting my drilling mechanism while drilling in the mine wall.

A prior application, Serial Number 268,783, filed April 9, 1928, shows an improved form of drilling mechanism in combination with a mining machine truck. My present application uses the same form of drilling mechanism shown therein but shows said drilling mechanism mounted on a small portable truck which serves as a support for my drilling mechanism during the drilling operations.

My invention may be more clearly understood by reference to the following drawings

wherein:

Figure 1 is a side elevation of the device embodying my invention drilling a hole in a mine wall;

Figure 2 is a rear elevation of the device

50 shown in Figure 1 with parts broken away

and in section to more clearly show the details of my invention;

Figure 3 is a fragmentary sectional view taken on line 3—3 of Figure 1;

Figure 4 is a side elevation of the device 55 embodying my invention in position to travel about the mine from working place to working place; and

Figure 5 is a side elevation of the device 60 embodying my invention in position to drill a hole in a mine wall with parts broken away and in section to more clearly show the details of my invention.

Referring now to the details of the embodiment illustrated in the drawings, 10 indicates 65 a main frame supported on an axle 11 and track wheels 12, 12, at its rearward end and a track wheel 13 having a double flange thereon at its forward end. The track wheel 13 is detachably mounted on a stud 14 fastened 70 in a support 15 projecting from the forward end of a drilling arm 16 pivoted at its rearward end to the rearward portion of the frame 10. A drilling mechanism 17 is supported on the forward end of the drilling 75 arm 16 for angular movement thereabout while power means for said drilling mechanism is supported at the rearward end of the main frame 10. Said power means herein comprises a motor which may be of any type 80 but which is herein preferably shown as an electric motor 18 having an armature shaft 19 thereon.

The main frame 10 is adaptable to rest in a horizontal position when the drilling mechanism 17 is being transported about the mine from drilling place to drilling place, but is adaptable to stand in a vertical position when a hole is to be drilled in a mine wall. Means 85 are provided to support said main frame in a vertical position between the mine bottom and the mine roof. Said means herein comprises a plurality of adjustable feet 20, 20, on the rearward or bottom portion of the main frame 10, and an adjustable bearing member 90 21 on the forward or top portion of the main frame 10.

The feet 20, 20, are mounted on balls 22, 22, for rotatable movement thereabout integral with shafts 23, 23, threaded in the bot-

tom of the main frame 10. Hand wheels 24, 24, are fixed to the threaded shafts 23, 23, so that rotation of said hand wheels causes movement of the threaded shafts 23, 23, in the main frame 10 to adjust the feet 20, 20, with respect to said frame. Likewise the bearing member 21 is mounted on a ball 25 integral with a shaft 26 threaded in the forward or top portion of the main frame 10 and a hand wheel 27 is fixed to said shaft to turn said shaft for adjusting the pressure of the bearing member 21 on the mine roof when the main frame 10 is in an upright position.

The drilling arm 16 is fixed to a housing 30 at its rearward end. The housing 30 has a stud 31 projecting from one end thereof which is journaled in the main frame 10. The opposite end of said housing abuts the motor 18 and is attached thereto. The motor 18 has a stud 32 projecting from its outer end which is also journaled in the main frame 10 so that said housing and motor may be rotatably moved about the studs 31 and 32 in the main frame 10. The armature shaft 19 extends through the housing 30 and is journaled therein. A worm 35 is integral with the armature shaft 19 and meshes with and drives a worm gear 36 keyed to a shaft 37 journaled within the drilling arm 16 and extending the entire length thereof. A member 38 having the projection 15 for supporting the track wheel 13 integral therewith is fixed to the forward end of the drilling arm 16. Said member has a supporting member 40 trunnioned thereon for supporting the drill rotating and feeding mechanism so said drilling mechanism may be moved angularly with respect to the drilling arm 16.

When the main frame 10 is supported in an upright or drilling position, the drilling arm 16 is held in the desired position with respect to said main frame by means of a plurality of straps 41, 41, extending from the main frame 10 to the drilling arm 16. Nuts and bolts generally indicated at 42 and 43 are provided to hold the straps 41 in the desired position with respect to the main frame 10 and drilling arm 16 so said drilling arm may be held in its various positions with respect to the main frame 10 by means of said straps. Likewise a strap 44 extends from the supporting member 40 to the drilling arm 16 to hold said supporting member and the drilling mechanism 17 in the various desired positions of adjustment with respect to the drilling arm 16. A nut and bolt generally indicated at 45 is provided on the supporting member 40 and a nut and bolt indicated at 46 is provided on the member 38 to hold said strap to the supporting member 40 and the member 38 and to hold the supporting member 40 and drilling mechanism 17 in the desired angular relation with respect to the drilling arm 16.

65 A drilling mechanism 17 is similar to that

described in my prior application, Serial Number 268,733, filed April 9, 1928, so will not herein be described in detail. A gear 48 is journaled in the supporting member 40 on its hub and has a threaded shaft 49 passing through the hub of said gear and feathered therein so said shaft may move through said gear for substantially its entire length. Threaded jaws 50 are provided on the supporting member 40 to engage said threaded shaft to move said shaft through the gear 48 as said gear is rotating said shaft. The jaws 50 are engaged or disengaged with the threaded shaft 49 by means of a hand operated disc 51. Suitable frictional means controlled by a hand wheel 52 are also provided to stop feeding or translational movement of the threaded shaft 49 upon overload of the drilling mechanism. The threaded shaft 49 is hollow and has a drill 53 held therein by means of a chuck 54.

The spur gear 48 is driven by means of a spur gear 55 keyed on the end of the shaft 37. Provision is made for driving the gear 48 from the gear 55 at the several permissible angles of said gears relative to each other, by arranging the pivoted axis of the members 38 and 40 so it will coincide with the pitch circles of both gears 48 and 55, and providing said gears with relatively deep teeth chamfered at their edges to prevent binding between said gears.

It may here be observed that rotation of the armature shaft 19 of the motor 18 will drive the drill 53 both translationally and rotationally by means of the worm 35, worm gear 36, shaft 37, spur gears 55 and 48, and the threaded shaft 49 and threaded jaws 50 at the several permissible angles of the drilling mechanism 17 with respect to the drilling arm 16.

Referring now in particular to Figures 1 and 4, Figure 4 shows the drilling mechanism 17 in transport position. Said drilling mechanism is supported on the rearward wheels 12 on the main frame 10 and on the forward wheel 13 on the drilling arm 16, a portion 60 on the main frame 10 bearing against the drilling mechanism 17 so the forward portion of said main frame may be supported on the double flanged track wheel 13. It should be noted that the double flanged track wheel 13 is removable from the stud 14 and is held thereon by means of a nut 61 so said wheel may be removed when the drilling mechanism is in drilling position. The main frame 10, wheels 12 and 13, and drilling mechanism are of as light material as possible to give the required strength so the entire drilling mechanism may be moved on the wheels on the mine bottom beyond the mine rails to the face of the coal where it is desired to place a drill hole.

The drilling mechanism being at the face of the coal, the main frame 10 is put in an

upright position. The feet 20, 20, are adjusted so said frame will stand evenly on the mine floor and the bearing member 21 is adjusted to bear against the mine roof to hold the main frame 10 in a vertical position. The main frame 10 therefore forms a jack to support the drilling mechanism 17 which is adjusted on the drilling arm 16 so as to drill at the desired angle and height with respect to the mine wall. Wedges 62 and 63 are inserted between the top portion of the drilling mechanism 17 and the mine roof to aid in holding said drilling mechanism in a steady position while drilling. The drilling mechanism 17 is now in position to drill a hole in a mine wall in the usual manner, as for instance that described in my prior application, Serial Number 268,733, filed April 9, 1928, and after the hole has been drilled said drilling mechanism may be moved along the mine wall to drill other holes therein or placed on the mine rails and be moved to the next place where it is desired to place a drill hole.

It may now be seen that I have provided a simple and compact drilling mechanism which may be easily transported from drilling place to drilling place. It may also be seen that while my drilling mechanism is simple of construction and light of weight that it is strong enough to stand up under all drilling conditions and that a motor is provided remote from the drilling mechanism itself which is therefore larger and more powerful than could ordinarily be mounted on the drilling mechanism itself and still be easily handled.

Although I have shown and described one form in which my invention may be embodied, it will be understood that alterations may be made in the construction or arrangement of the various parts thereof without departing from the spirit and scope of the invention. Furthermore, I do not wish to be construed as limiting myself to the particular embodiment illustrated, excepting as it may be limited in the appended claims.

I claim as my invention:

1. In a portable drilling mechanism, a main frame, a drilling arm pivotally mounted on said main frame, drilling mechanism mounted on said drilling arm for angular movement thereabout, and adjustable bearing means on each end of said main frame to support said main frame between a mine wall and a mine bottom so said main frame may comprise a jack to support said drilling mechanism when drilling in a mine wall, a pair of wheels on said main frame, and a wheel on said drilling arm so said main frame and drilling arm may support said drilling mechanism for movement from drilling place to drilling place.

2. In a portable drilling mechanism, a main frame, a drilling arm pivotally mounted

ed on said main frame, drilling mechanism mounted on said drilling arm for angular movement thereabout, and adjustable bearing means on each end of said main frame to support said main frame between a mine wall and a mine bottom so said main frame may comprise a jack to support said drilling mechanism when drilling in a mine wall, a pair of wheels on said main frame, and a wheel on said drilling arm so said main frame and drilling arm may support said drilling mechanism for movement from drilling place to drilling place, said wheels being so arranged on said main frame that said adjustable bearing means on each end of said main frame will be out of engagement with the mine bottom when said drilling mechanism is supported for movement from drilling place to drilling place.

3. In a portable drilling mechanism, a main frame, a drilling arm pivotally mounted on said main frame, drilling mechanism mounted on said drilling arm for angular movement thereabout, adjustable bearing means on each end of said main frame to support said main frame in a vertical position in a mine for holding said drilling mechanism so said drilling mechanism may drill a hole in a mine wall, a pair of wheels on said main frame and a wheel on said drilling arm for supporting said main frame in a horizontal position for transporting said drilling mechanism from working place to working place.

4. In a portable drilling mechanism, a main frame, a motor on said main frame, a drilling arm having a shaft therein connectible with said motor at one end thereof, drilling mechanism mounted on said drilling arm for angular movement thereabout, a geared connection from said shaft to said drilling mechanism, adjustable bearing means on each end of said main frame to support said main frame in a vertical position in a mine to hold said drill mechanism for drilling a hole in a mine wall, a pair of wheels on said main frame and a wheel on said drilling arm cooperating with said wheels on said main frame for supporting said main frame in a horizontal position for transporting said drilling mechanism from working place to working place.

5. In a portable drilling mechanism, a main frame, a pair of feet on one end of said main frame adaptable to rest on a mine bottom, a bearing member on the opposite end of said main frame adaptable to bear against a mine roof to hold said main frame in a vertical position, a motor pivotally mounted on said main frame adjacent said feet, a drilling arm pivotally mounted on said main frame on the same pivotal axis as the pivotal axis of said motor, drilling mechanism on the opposite end of said drilling arm driven by said motor, and a plurality of wheels on said main frame and said drilling arm for

supporting said main frame in a horizontal position for transporting said drilling mechanism from working place to working place.

6. In a portable drilling mechanism, a main frame, a drilling arm pivotally mounted at one of its ends on said main frame to pivot about an axis transversely of said main frame, means for holding said drilling arm in its various positions of pivotal adjustment with respect to said main frame, drilling mechanism mounted on the opposite end of said drilling arm for angular movement thereabout, means on said main frame for supporting said drilling mechanism when drilling in a mine wall when said main frame is tilted in one position and additional means on said main frame and drilling arm for supporting said drilling mechanism for movement from drilling place to drilling place 20 when said main frame is tilted in another position.

7. In a portable drilling mechanism, a main frame, a drilling arm pivotally mounted at one of its ends on said main frame to pivot about an axis transversely of said main frame, means for holding said drilling arm in its various positions of pivotal adjustment with respect to said main frame, drilling mechanism mounted on the opposite end of said drilling arm for angular movement thereabout, means on said main frame for supporting said main frame as a jack to support said drilling mechanism when drilling in a mine wall, and additional means on said main frame and drilling arm for supporting said drilling mechanism for movement from drilling place to drilling place, said means on said main frame for supporting said main frame as a jack being out of engagement 35 with the ground when said drilling mechanism is supported for movement from drilling place to drilling place.

8. In a drilling mechanism, a main frame, a motor on said main frame adjacent one end thereof, a motor shaft, a drilling arm pivotally mounted on said main frame at one end to pivot about an axis coaxial with said motor shaft, drilling mechanism mounted on the opposite end of said drilling arm for angular movement 45 thereabout, said main frame being tilttable in one position to form a jack to support said drilling mechanism when drilling in a mine wall and tilttable in another position to form a truck for moving said drilling mechanism about the mine bottom.

9. In a drilling mechanism, a main frame, a motor on said main frame having a motor shaft extending transversely of said main frame, a drilling arm pivotally mounted on said main frame at one end to pivot about an axis coaxial with said motor shaft, drilling mechanism mounted on the opposite end of said drilling arm for angular movement 60 thereabout, means within said drilling arm

for driving said drilling mechanism from said motor in all positions of adjustment thereof, said main frame being tilttable in one position to form a jack to support said drilling mechanism when drilling in a mine wall and tilttable in another position to form a truck for moving said drilling mechanism about the mine bottom.

Signed at Chicago, in the county of Cook and State of Illinois, this 18th day of September, A. D. 1928.
